UNITED STATES PATENT OFFICE

2,569,315

LIQUID FUEL BURNER WITH RADIANT HEATING ELEMENT

Jack Imber, Greenford, England

Application January 18, 1947, Serial No. 722,873
In Great Britain January 23, 1946

3 Claims. (Cl. 126—96)

This invention relates to liquid fuel burners, and more particularly to paraffin burners of the wick type above which a radiant element is disposed. The radiant elements used hitherto have been subject to the disadvantages that either they reduce the airflow through the burner to such an extent that the normal functioning of the burner is adversely affected or they radiate heat back on to the burner to an undesirable degree. These disadvantages not only prevent uniform heating but in the one case the burner tends to smoke causing the element to become covered with carbon and cease to glow. In the other case, a burner may be correctly adjusted when cool but after lighting, increased vapourization due to heat radiated back on to the burner from the element may cause the burner to smoke.

The object of the present invention is to provide an improved construction or arrangement of radiant element designed to avoid the disadvantages described in the preceding paragraph.

According to the invention an improved radiant element for use with a liquid fuel burner comprises an assembly of thin strips or filaments of heat resisting material disposed in positions substantially parallel to or slightly inclined to the direction of air flow through the burner.

According to the preferred form of the invention a radiant heating element for use with a liquid fuel burner comprises an assembly of thin strips or filaments of heat resisting material, the components of said assembly being connected to upper and lower rings of heat resisting material, and the upper ring being of smaller diameter than the lower ring which is formed for attachment to a burner.

Reference will now be made to the accompanying drawings which show examples of heating elements constructed according to the invention and in which:

Fig. 1 is a sectional elevation of an all-metal heating element,

Fig. 2 is a plan of the element shown in Fig. 1,

Fig. 3 is an elevation looking in the direction of the arrow in Fig. 2,

Fig. 4 is a sectional elevation of an alternative form of construction,

Fig. 5 is a plan of the element shown in Fig. 4, and

Fig. 6 is an elevation looking in the direction of the arrow in Fig. 5.

Referring first to Figs. 1 and 3, a radiant element is shown applicable to a paraffin burner of the annular wick type. This element comprises a number of thin strips *a* of a heat resisting metal united at the top and bottom by rings *b* and *c* of the same metal. The upper ring *b* is of smaller diameter than the lower ring *c* so that the strips *a* lie in directions slightly

inclined to the direction of air flow through the burner. The spaces between the strips are slightly greater than the widths of the individual strips. The lower ring *c* is formed integral with supports *d* secured at their lower ends to a ring *e* adapted to seat on the outer wick tube and support the complete radiant element an appropriate distance above the upper edge of the wick. The outer cylindrical wall *f* of the depending portion of the ring *e* is provided with a circumferential row of apertures *g*, to reduce heat conduction from the radiant element to the outer wick tube of the burner employed.

The radiant element above described may be formed conveniently from a flat sheet of metal from which portions are stamped out to form the strips *a* and the upper and lower rings *b* and *c*. The sheet is then bent into an upwardly converging frusto-conical form and the meeting edges united as by spot welding them together.

In the form of the invention shown in Figs. 4-6 an element is used in which the radiant portion is mainly composed of filaments disposed substantially parallel to the direction of the air-flow through the burner above the flame. These radiant filaments may be composed of asbestos string with nickel wire centre wound on a supporting frame of heat resisting material in such a manner that the component filaments are all inside the frame. The frame is in the form of two rings *f* and *g* rolled from flat strip and disposed one above the other so that they lie substantially edge on to the air-flow and thus offer the least possible resistance to it. The upper ring *f* is supported from the lower ring *g* by arms *h* which may be integral with the rings or welded to them, which arms *h* are radiating members to the degree to which they are heated by the flame of the burner. The upper edge of the upper ring *f* and the lower edge of the lower ring *g* are provided each with a number of small projections *i* around which are passed loops of the asbestos wound wire *k* to form substantially vertical stretches extending between the two rings and on the inside of each ring. In order to obtain the best results it is desirable to have the upper supporting ring of smaller diameter than the lower. This brings the filaments more nearly parallel to the direction of air flow through the burner and ensures the maximum heating of each filament uniformly along its length. The element shown in Figs. 4-6 is shown supported from a ring *e* as in Figs. 1-3 but this form of mounting is shown by way of example only as the element of either form can be supported in a variety of ways according to the particular burner construction to which it is applied.

In each of Figs. 1 and 4, the upper portion 60 of a liquid fuel burner of known construction

is diagrammatically shown that is adapted to operate the radiant elements above described, said burner construction being, for example, a part of the burner structure shown and described in United States Patent No. Re. 18,061 which issued May 5, 1931, to Cortland W. Davis for an improvement in Blue Flame Mantle Lamps. As shown in Figs. 1 and 4, the burner includes an outer wick tube 12, an annular wick 13, an inner wick tube 14, a flame spreader 15 carried by the upper end of the inner wick tube 14 to supply inner air to the annular flame of the burner, and a burner cone 16 concentrically around and having its inner circular edge 17 substantially spaced from the flame spreader 15, to supply outer air to the burner flame, all of these burner parts being related to each other and operating to produce a blue annular flame in the manner generally and more specifically described in said reissued patent.

The annular flame produced by the burner extends upwardly and centrally into the radiant element of each of Figs. 1 and 4, through the circular, central opening 17 in the ring e forming a part of each of said radiant elements, which opening 17 surrounds and is spaced from the base of the annular flame, to project into and against said flame, the outer air required to effect complete combustion of the vaporized fuel. It will be noted that the lower portion of the ring e in each case, is of substantially the same form and proportions, as the burner cone 22 of said reissued patent. In the present application, the burner cone 16 is shown as supported from the outer wick tube 12 by a frusto-conical baffle 18 containing an annular row of large diameter perforations 19 to adequately supply air from the lower portion of the burner (not shown), to beneath the burner cone 16, for direction thereby inwardly to constitute the outer air supplied to the burner flame. The radiant elements of the invention may have other forms of support from the burner structure, depending on the type and form of the burner employed in any case.

In using either form of the invention described, it has been found that the best results are obtained if the lower ring of the support is between 1 and 1½ times the wick diameter and is situated from $\frac{1}{4}$ to $\frac{3}{4}$ of the wick diameter above the burner. The size ensures that the ring does not materially affect the air flow through the burner, whilst the spacing from the burner ensures that the heat radiated back on to the burner is not excessive. Support rings made in accordance with the above dimensions are heated to redness by contact with the glowing strips or filaments and form part of the radiant element.

The diameter and position of the upper support ring must be chosen to suit the particular burner used, whereby the temperature of this ring can be raised to that of dull red heat.

I claim:

1. In combination, a radiant heating element and a liquid fuel burner of the annular wick type, said heating element including vertically extending radiating members in upwardly converging frusto-conical arrangement around a vertical axis, an upper and horizontally disposed first ring connected with the upper ends of said radiating members, a lower and horizontally disposed second ring of larger diameter than said first ring and connected with the lower ends

of said radiating members and having supporting connection with said upper ring, a mounting ring spaced below and substantially parallel with and supporting said second ring and having a central flame admission opening, and a liquid fuel burner of the annular wick type coaxial with said heating element and supporting said mounting ring and for projecting an annular flame upwardly through said central opening and between and to directly heat said radiating members.

2. In combination, a radiant heating element and a liquid fuel burner of the annular wick type, said heating element including vertically extending radiating members in upwardly converging frusto-conical arrangement around a vertical axis, an upper and horizontally disposed first ring connected with the upper ends of said radiating members, a lower and horizontally disposed second ring of larger diameter than said first ring and connected with the lower ends of said radiating members and having supporting connection with said upper ring, a mounting ring spaced below and substantially parallel with and supporting said second ring and having a central flame admission opening, and a liquid fuel burner of the annular wick type coaxial with said heating element and supporting said mounting ring and for projecting an annular flame upwardly through said central opening and between and to directly heat said radiating members, said radiating members comprising spaced metal strips integral with said first and said second rings.

3. In combination, a radiant heating element and a liquid fuel burner of the annular wick type, said heating element including vertically extending radiating members in upwardly converging frusto-conical arrangement around a vertical axis, an upper and horizontally disposed first ring connected with the upper ends of said radiating members, a lower and horizontally disposed second ring of larger diameter than said first ring and connected with the lower ends of said radiating members and having supporting connection with said upper ring, a mounting ring spaced below and substantially parallel with and supporting said second ring and having a central flame admission opening, and a liquid fuel burner of the annular wick type coaxial with said heating element and supporting said mounting ring and for projecting an annular flame upwardly through said central opening and between and to directly heat said radiating members, said burner including a burner cone for directing outer air to the flame of the burner, said mounting ring including a horizontally disposed disk of metal containing said central opening and comprising said burner cone.

JACK IMBER.
